UNITED STATES PATENT OFFICE.

JOHN AXEL FERDINAND SVENSON, OF SCRANTON, PENNSYLVANIA.

DRAWING-TABLE.

SPECIFICATION forming part of Letters Patent No. 415,691, dated November 19, 1889.

Application filed June 4, 1889. Serial No. 313,088. (No model.)

To all whom it may concern:

Be it known that I, JOHN AXEL FERDINAND SVENSON, having declared my intention of becoming a citizen of the United States, residing at Scranton, in the county of Lackawanna and State of Pennsylvania, have invented certain new and useful Improvements in Drawing-Tables; and I do hereby declare the following to be a full, clear, and exact description of the invention, such as will enable others skilled in the art to which it appertains to make and use the same.

The object of my invention is to produce a drawing-table which shall combine all the useful properties of the older devices, wherein the working-surface of the board was always held horizontal, with the more recent improvements upon these, which only offered a vertical drawing-board surface. Closely depending on this greater range of utility, my improvement embraces a new and superior parallel-ruling device.

Figure 1 is an elevation of my improved drawing-table. Figs. 2 and 3 are sectional views of the same. In Figs. 1, 2, and 3 the drawing-board is removed in order to show more clearly the essential mechanism. Fig. 4 is a detached plan of the movable frame which carries the drawing-board, showing the parallel-ruling device. Figs. 5 and 6 are sectional elevations of the same. Figs. 7 and 8 are detached views showing in detail the arrangement of fastening the ruler to the cords. Fig. 9 is a modification of the parallel-ruling device.

The following is a full description of my improvement:

a is the frame upon whose lower member the board rests when in place. This frame moves in slides *b b'*, and is balanced by a weight *w* through two cords *i* and *i'*, which are secured to the frame and carried over pulleys *c c' d e f*, and finally fastened at their opposite ends to the table *T*. Each of the pulleys *d*, *e*, and *f* has, of course, two grooves in the rim. The counter-weight is suspended from the center pin of the movable pulley *f*.

The slides *b b'* are, near their upper ends, united by the cross-piece *g*, to which the support *h* is hinged. The slides *b b'* are also hinged at their lower ends to a projection

built up from the stationary part of the drawing-table. The object of all these hinges is to allow the parts to take the positions they occupy in Fig. 3.

It is seen in Fig. 2 that the strain in the cords *i i'* tends to force the lower ends of support *h* into recesses formed for this purpose in pieces *k*, thus making impossible any accidental slip of said lower ends of support *h*. In effecting the change from position of board in Fig. 1 to that in Fig. 2 the draftsman pulls with one hand the support *h* forward as far as indicated by dotted lines *h'* in Fig. 2. His other hand, which had previously grasped the upper side of frame *a*, can now gradually lower the system down to rest upon the posts *l*, which have pegs *x*, that penetrate the slides *b b'* and fit into holes made for this purpose in the edges of frame *a*. The small wheels *m* facilitate the descent by rolling down the curved incline *k*. When placed in the position of Fig. 3, the frame *a* is prevented from moving out of slides *b b'* by the pegs *x*, described above. The mere lifting upward of frame *a* suffices to restore the system to the position of Fig. 2, all the movable parts adjusting themselves automatically to this position. The pulley *d* performs a very important function in this change of the board from one position to the other; in fact, it is the very thing which makes this change practicable. This will become apparent from an examination of Fig. 3. Here it is seen that the strain in the cords *i i'* between pulley *d* and pulley *e* has been made to take a direction nearly opposite to that in the cords between pulley *c'* and pulley *d*, the effect of which is to neutralize the downward pull caused by the heavy counter-weight *w*, which, were it not for this disposition of pulley *d* and cords *i i'*, would very seriously oppose any attempt at raising the system to the position of Fig. 2.

From the foregoing description it becomes evident that when the drawing-board occupies the position of Fig. 2 it can be moved up or down at will to accommodate the draftsman in a standing or sitting position. Besides, he can while sitting move the frame and board so high up as to leave a sufficiently open space over the table *T*, whereby this is converted into a very con-

venient writing-desk. Add to this the position in Fig. 3, and it cannot fail to be noticed that my invention can well lay claim to superiority, the various positions of the drawing-board, so easily changed from one to the other, affording great convenience and rest to the draftsman.

Before explaining my improved parallel-ruling device it will be well to remark that in heretofore-existing devices for operating the ruler on a vertical drawing-board the weight of this ruler was counteracted by a balance-weight attached in such a manner that the board could not be placed in a horizontal position without disturbing the proper relation between them. Therefore in order to accommodate the above-described changes in the position of the drawing-board I have invented a new device, which in all positions shall give the ruler a perfect motion.

In Fig. 4, o is the ruler, which at s and s' is fastened to the cords z z' . These cords, running over pulleys q q' q^2 q^3 , constitute in combination with the ruler o the parallel-ruling device. RR' are the balance-weights, which at all times hold the ruler in equilibrium. The cord z is placed in position in the following manner: Beginning, for instance, at the balance-weight R , it is led in the direction of the arrows in dotted lines upward and over pulley q , then down to s , where it takes a turn around the square projection of the bar u , which in larger scale is shown by Figs. 7 and 8. Further, the cord runs down and around the pulley q^3 , then to the right and around pulley q^2 , ascending from thence to balance-weight R' . The other cord runs from R' , as indicated by arrows in full lines, over pulley q' to s' and around the square at s' , then over pulley q^2 to the left and over pulley q^3 to balance-weight R . The two pulleys q^2 and q^3 are double-grooved to accommodate the two cords. The arrows also indicate the path of two corresponding points of the cords when the ruler is moved toward the lower edge of the board, and it is then evident that since the two points s and s' always move in the same direction and to the same extent the device must produce a perfect parallel motion. The simplicity of my improvement and on this score its superiority over previous contrivances is at once apparent when it is considered that no separate pulleys are needed for the balance-weights. Moreover, my arrangement of pulleys and cords is such that the balance-weights secured to the latter slide on the surface of frame a , which important feature secures a perfect equilibrium between ruler and balance-weights in all positions of the drawing-board, since they always move in the same plane.

As shown in Figs. 7 and 8, the bar u has at s a projection which is partly round and partly square. The round part moves in the guides y . (Shown by Figs. 4 and 5.) The square is a fastening for the cord, as pre-

viously described. The bar is at u' formed into a socket resting on the washer u^2 and embracing the head of adjusting-screw v . By this means the ruler o can be given any angle with the bar u and then clamped in position. The pendulum-like connection between the cords z z' and the ruler o permits this latter while in motion to be swung away from the drawing-board without any interference with its correct parallel motion. This arrangement offers a great advantage, since the ruler can without blotting be passed over a wet ink-line, and also in combination with the previously-described adjusting-screw v and socket u' it forms a ready means for adjusting the ruler to any thickness of drawing-board.

In Figs. 4, 6, 7, and 8, P is a shelf attached to the ruler and designed for holding instruments when the drawing-board occupies its vertical position. When the board is horizontal, this shelf can be folded flat against the ruler by means of hinges o' .

In the modification shown in Fig. 9 the cords are crossed between the pulleys q^2 and q^3 instead of running parallel. The operation is the same in all respects.

What I claim is—

1. An adjustable drawing-table comprising a frame to hold a drawing-board hinged at one edge, a support hinged at or near the opposite edge of said frame, and a weight suspended from said frame and hinged support, the lower end of said hinged support being free, whereby said frame and support may be folded together and the frame thereby adjusted to different angles, substantially as set forth.

2. An adjustable drawing-table comprising a frame to hold a drawing-board hinged at one edge, a support hinged at or near the opposite edge of said frame, a weight suspended by a cord from said frame and hinged support, and a fulcrum d on said support, over which said cord passes, the lower end of said support being free, whereby said frame may be folded together and the frame thereby adjusted and held at different angles, substantially as described.

3. In an adjustable drawing-table, the combination of the following elements: a table T , an adjustable frame to hold a drawing-board hinged at one edge to said table, a support hinged to said frame and having its free end resting and movable upon said table, a cord secured at one end to said frame near its lower edge, passing over pulleys on said support, and secured at its other end to said table, and a weight suspended by said cord below the table, all substantially as set forth.

4. In a drawing-table, the combination of the following elements: a table T , having a vertical standard k , one edge of which forms an inclined track, a frame hinged to said table, a support hinged to said frame and having its free end resting upon said track, a cord connected at one end to said frame and at the

other to said table and having an intermediate fulcrum upon said support, and a weight suspended by said cord below the table, all substantially as and for the purposes set forth.

5 5. The combination, with the table T, of a frame hinged thereto, a support hinged to said frame and having a rolling bearing on the table, and a system of counterbalancing devices for holding and permitting the adjustment of to said frame and support, substantially as set forth.

6. The combination, with the table T, having the standard k, with its curved and inclined track, of the support h, having a roller 15 resting and movable upon said track, and the cords i i' and weight w, all substantially as set forth.

7. The combination, with the table T, having the standard l and pin x at its rear, of the 20 frame a b, hinged to the front of said table, substantially as set forth.

8. In a drawing-table, the combination, with the table T, of the hinged frame a b, the auxiliary supporting-frame h, hinged thereto, the 25 cords i i', secured at one end to said frame and at the other to said table, the guide-pulleys c c' e, the fulcrum-pulley d, and the weight w, suspended on the cord, all substantially as described.

30 9. The combination, with the table T, of the grooved ways b b', hinged thereto, and the sliding frame a, said ways and frame forming an adjustable holder for a drawing-board, substantially as set forth.

35 10. The combination, in a drawing-table, of

a parallel-ruler, balanced cords for sliding the same, and a yielding connection between said ruler and cords, substantially as set forth.

11. The combination, with a drawing-table, of balanced cords running on pulleys, substantially as set forth, a parallel-ruler, and the bar u, connected to said ruler and cords, substantially as set forth.

12. The combination, with the table having the pulleys q q' and double-grooved pulleys q² q³, of the cords z z', the sliding balance-weights R R, and the adjustable ruler o, substantially as set forth.

13. The combination of a table having guides y, the ruler o and cords for moving it, 50 and the arms u, connected to such cords and having a guide-roller, substantially as set forth.

14. The combination, with the ruler o, of the arm u, having hook u', and the clamping-nut v, substantially as set forth.

15. The combination, with the cords z z' and with the ruler o, of the arms u, having square projections to serve as fastenings for a turn of the cords, substantially as set forth.

16. The combination, with the ruler, of a hinged shelf, as P, substantially as and for the purposes set forth.

In testimony whereof I have affixed my signature in presence of two witnesses.

JOHN AXEL FERDINAND SVENSON.
